Des. 154

Thomas Barry (assignor of) ^{attenuated} Samuel H. Rausen ^{attenuated} New York, N.Y.
Letters Patent (Design No 154) dated Oct. 2: 1847.

The schedule referred to in these Letters Patent and
making part of the same.

Be it known that I Thomas Barry of the City and State
of New York have produced a new and useful ornamental
design for an air-tight Stove, and I do hereby declare that
the annexed and accompanying drawing, is a full and accurate
delineation of a stove constructed after my design, the side and
back not shewn being similar and symmetrical with the
side and front as represented, except that the back has the
usual opening & flange for the applying and fitting the pipe
or smoke flue to the stove.

What I claim as my invention and desire to secure by
Letters Patent, is, the combination and arrangement of ornamental
figures and forms, as represented in the accompanying drawing,
herewith deposited in the Patent Office, making an ornamental
air-tight Stove.
